CLAIM

The ornamental design for an escutcheon, as shown and described.

DESCRIPTION

FIG. 1 is a front side perspective view of an escutcheon according to my new design.

FIG. 2 is a front view of the escutcheon as in FIG. 1.

FIG. 3 is a top view of the escutcheon as in FIGS. 1–2.

FIG. 4 is a back view of the escutcheon as in FIGS. 1–3.

FIG. 5 is a bottom view of the escutcheon as in FIGS. 1–4.

FIG. 6 is a right side view of the escutcheon as in FIGS. 1–5; and,

FIG. 7 is a left side view of the escutcheon as in FIGS. 1–6.

The broken line showing of the handle and door lock area is included for the purpose of illustrating environmental structure only and forms no part of the claimed design.
